CLOTHESPIN

Nicholas A. Volpe, Burbank, Calif.

Application February 21, 1950, Serial No. 8,050

Term of patent 3½ years

(Cl. D17—6)

To all whom it may concern:

Be it known that I, Nicholas A. Volpe, a citizen of the United States, residing at Burbank, in the county of Los Angeles and State of California, have invented a new, original, and ornamental Design for a Clothespin, of which the following is a specification, reference being had to the accompanying drawing, forming a part thereof.

Fig. 1 is a perspective view of a clothespin, showing my new design; Fig. 2 is a side elevation of the clothespin; and, Fig. 3 is an end elevation of the clothespin.

I claim:

The ornamental design for a clothespin, as shown.

NICHOLAS A. VOLPE.
